HAULING AND LIFTING APPARATUS

Simon Faure, Firminy, France

Application December 9, 1930, Serial No. 501,044,
and in France December 26, 1929

8 Claims. (Cl. 254—135)

This invention relates to rope hauling apparatus of the kind wherein one automatic one-way clip is reciprocated as by a hand lever with respect to a second automatic one-way clip acting in the same direction as the first. With such apparatus the rope can be hauled against a load in the opening direction of the clips, but cannot be paid out under load as is desirable when such apparatus is used say in conjunction with pulleys or like tackle for lifting and lowering loads. The invention consists primarily therefore in providing apparatus of the kind in question with reversing means which when set in action automatically hold each clip open when its motion relative to the rope is such that the clip would normally grip. The arrangement must be such that both clips are not open together, though the reversing means may be adapted by a further adjustment to open both clips to facilitate threading of the rope through the apparatus.

A simple embodiment of the invention is illustrated in the accompanying drawings.

Figure 1 is a side view.

Figure 2 is a front view, the front plate being removed.

Figures 3, 4 and 5 are details of one of the two clips, being respectively a vertical axial section of the lower clip, a side view, and a view in plan.

Figure 6 shows the apparatus on a larger scale in position for lifting or hauling.

Figure 6a is a detail section on the line VIa—VIa of Figure 6.

Figures 7 and 8 show the apparatus in position for paying out the cable under load, with the hand lever in the uppermost and lowermost position respectively.

Figure 9 shows the apparatus in position for release of the cable.

Figure 9a is a detail section on the line IXa—IXa of Figure 9.

The framework of the apparatus comprises a channel section member 3 bent to form three sides of a rectangle, to which are bolted parallel front and back plates 1 and 2. The body carries at the top a cable or rope guiding tube 4. The cable 5 carrying the load hook 6 enters the apparatus through the guide tube, passes between the two clips and leaves at the bottom. At the bottom the apparatus has an anchoring hook 7.

Inside the frame are two identical clips, an upper and a lower. The upper clip of which a section appears in Figure 2 is mounted between two parallel cheeks, such as 8, connected together by studs 80, and lying against the plates of the body 55 of the apparatus. Two pairs of links 9 and 10 pivoted to the cheeks 8 at their inner ends and at their outer ends to the jaw 11 control the motion of the latter. An intermediate pair of links 12, are pivoted at one end 12a to the cheeks 8. At the other end they are pivoted to a jaw 15, by a

pivot 13 which passes through an elongated slot 14 in the jaw 11 so that when the latter moves up or down the jaw 15 is also moved. The links 9, 10 and jaw 11 form a deformable parallelogram and the whole assembly with the links 12 and jaw 15 all move together. As the links 12 are not parallel with the links 9, 10 but are slightly more downwardly inclined, when the jaws are moved upwards the jaw 15 moves further to the right than the jaw 11 and the jaws grip the cable or rope. The clip is normally urged into the gripping position by a spring 16 bearing at its upper end against one of the studs 80 and at its lower end against a pin 10a joining extension 10b of the links 10. It will be observed that any tendency of the cable to move upward with respect to the clip will tighten the grip, while with any downward movement the clip will automatically open to let the rope slide through if the clip is not otherwise held closed.

The lower clip, enclosed between cheeks such as 17, Figure 3 being in all respect similar to the upper, need not be described. Corresponding parts have been given the same references indexed.

As shown in Figure 5 the parts of the jaws 11, 11', 15 and 15' which grip the cable have curved surfaces 18 corresponding to the surface of the cable, to obtain the best possible grip without damage to the cable.

The upper clip is maintained in position at the top of the apparatus, but with slight transverse play by means of the studs 80 which connect cheeks 8 and pass through suitable apertures in plates 1 and 2. A handle 19 serves for carrying the apparatus, which is operated by a lever 20 pivoted on a pin 20a which as described below can be mounted in either of the apertures 21 or 25 in the body. This lever gives the lower clip a rectilinear movement guided by the frame, through the agency of a stirrup 22 pivoted at 23 to the clip and at 24 to the lever. Holes such as 25 can be provided along the lever to permit changes of ratio and therefore of speed of the apparatus, by displacement of the pivot pin 20a shown in the aperture 21 in Figure 2.

A plate 26 which is used to reverse the normal action of the apparatus is mounted on the plate 1 by two frictional holding devices allowing it to be moved in two directions, i. e. up and down and transversely.

The plate 26 has a large aperture 27 described below and a small aperture 29 through which projects the pivot 30 joining the links 10 with the jaw 11. The aperture 29 is shaped as shown, the left hand end being of such size as to prevent relative motion between the pin 30 and plate 26 while the right hand end is large enough to allow sufficient relative motion for the upper clip to open and close without movement of plate 120

26 when the later is in such a position (see Figure 6) as to bring this part of aperture 29 into register with the pin 30. A third aperture 31 serves to receive a cam 32 mounted upon and actuated by a lever 33 operated by a handle 34. The lever can turn about the pivot 35 riveted to plate 1 (see Figure 6a). The lever is pressed against the plate 26 and the latter against the plate 1 by spring 36 and cap nut 37, the parts 10 33, 26, 1 thus being held in frictional engagement. Two abutments 38 and 38' on the lever coat with pin 39 on the plate 26 to limit the movement of the lever 33, the first checking it in the hauling position of the apparatus, the 15 second in the paying out position.

At its lower end the plate 26 has an aperture 40 and is held to the plate 1 by frictional holding device 41 similar to that described above. A retaining device 42 enables the pivot 20a of the 20 lever 20 to be held in position, whether this pivot is mounted in the aperture 21, or the aperture 25. As will be seen in Figure 9a the device 42 secured to the plate 1 has two grooves 42a, 42b respectively adjacent the apertures 21 and 25. The pivot 20a has a shoulder 20b cut off at 20c; the pivot can be turned to bring the shoulder into the groove 42a and 42b as seen in Figure 9a, or it can be turned to bring the cut off part 20c adjacent the groove when the pin 30 can be withdrawn or inserted.

In the aperture 27 of the plate 26 is a substantially triangular plate 43 having a tail piece 43a. The greater part of the plate 43 lies in the same plane as the plate 26, but the tail piece 43a is bent outwardly as seen in Figure 1 so that it can move over plate 26 when necessary. There is an aperture 44 in plate 43 through which passes the moving pivot 45 of the upper links 9' of the lower clip. The aperture 44 is shaped as shown, similarly to aperture 29 described above, so that when the plate is in the position shown in Figures 7, 8 and 9 with the pin 45 in its left hand end the pin cannot move longitudinally with respect to the plate, but when the plate is in the position shown in Figure 6 with the pin at the right hand end of the aperture, the pin can move longitudinally with respect to the plate a distance sufficient for opening and closing the lower jaws. Through a 50 second aperture 46 in plate 43 allowing the latter a certain amount of longitudinal and transverse movement, there passes a pin 47 mounted on the cheek 17 of the lower clip, the pin carrying a similar device to that above described for holding the plate 43 in frictional engagement with the cheek 17. A slot (54, Figures 8 and 9) is provided in the plate 1 sufficiently long to allow for the motion of the pins 45 and 47 which is substantially along the line 28.

An abutment 48 with two opposite parallel ramps 49 and 50 is secured to the reverser 26 by a pivot 51 and a stud 52. The abutment can be removed and reversed when there is a change of ratio, that is to say when the pivotal axis of the lever is moved from 21 to 25, and in this position stud 52 passes through the aperture 53 in the abutment. Figures 6, 7 and 8 show one position and Figure 9 the other.

The apparatus operates as follows:—

1. Hauling or lifting

For this action the lever 33 of the reversing mechanism is moved to the left to the position shown in Figure 6. It will be observed that in this position the reversing mechanism is out of

action because the elongated parts of the apertures 29 and 44 are around their respective pivots 30 and 45 so that the plates 26 and 43 exert no control over the said pivots and over the jaws actuated thereby. The lever 20 shown pivoted in this figure at 21 is then actuated. During the downward movement of the lever the cable 5 tends to move the jaws of the upper clip downwards. They therefore open and the cable 5 slides in the upper clip. The lower clip on the contrary grips it. As the lever gives this clip a rectilinear movement guided by the frame 3, the cable is moved and with it the load which it supports, by an amount equal to the displacement of the lower clip.

During the upward movement of the lever, the lower clip releases the cable and leaves it free. But the latter is held by the upper clip which grips it and prevents its sliding. During this upward movement of the lever, there is no progression nor retrogression of the cable whatever the load carried by it.

It will be observed that as above described the reversing mechanism remains out of action during hauling or lifting.

2. Lowering or paying out under load

For executing this movement, the lever 33 of the reversing mechanism is turned to the right, to the position indicated in Figures 7 and 8. It will be convenient for purposes of description to assume this is done when the lever 20 is in its uppermost position as shown in Figure 7, though in practice the change can be made in any position of lever 20. As in the uppermost position of the lever there is no tension in the part of the cable below the upper clip, there is no pull on the lower clip and the frictional hold of the pin 47 on the plate 43 is sufficient to prevent the latter sliding with respect to pin 47, when the lever 33 is turned. This turning of the lever moves plates 46 and 43 to the right and the upper edge of aperture 44 in plate 43 causes pin 45 to move downwards towards the pin 47, thus opening the lower clip as will be readily understood by reference to Figure 3.

During the downward movement of the lever 20, the pins 45, 47 remain in the same relative position owing to the frictional grip of plate 43 against cheek 17 and the lower clip is held open during part of the stroke, the cable remaining gripped by the upper clip. At a certain point in the downward movement, the tail piece 43a of the part 43 strikes the ramp 49 of the abutment 48. This is carried by plate 26 which is held strongly in position by the pull in the upper clip which holds the plate 26 by the engagement of the pin 30 with the left hand end of aperture 29 in plate 26. From this moment, the plate 43 remains stationary while the pin 47, being mounted on cheek 17 which is being moved by the lever, slides along the aperture 46 thus moving pin 47 away from pin 44 which closes the lower clip and causes it to grip the cable. When the pin 47 has reached the upper end of the slot 46 further movement of the lever 20 must move plate 43 which through its tail piece 43a and the abutment 48 carries the plate 26 along and the upper clip will be opened, owing to the pivot 30 being moved downward by the left hand end of aperture 29 in plate 26.

As at this time the cable is gripped by the lower clip, the pull on the cable which is relatively great, will be tending to pull pin 45 in the jaw 11' away from pin 47 on cheek 17. This pull

will be greater than the resistance to motion of the plate 26 produced by the friction devices at 35 and 41. Consequently during the upward movement of the lever 20 when the lower clip 5 nears its uppermost position and the upper edge of plate 43 comes into contact with the upper edge of aperture 27 in plate 26, the plate does not check plate 43 while pin 47 moves upwardly, but on the contrary, plate 43 carries plate 26 upwardly and by raising pin 30 closes the upper clip. At this point the plate 26 can rise no further, consequently pin 45 and member 43 must remain stationary while pin 47 is raised towards pin 45 by the further motion of the lever lifting 10 the lower clip, and accordingly the latter opens while the pin 47 slides in slot 46 in the stationary plate 43. The cycle can then be repeated.

3. Liberation of the cables

20 For this, the cable must of course be free from load, i. e. free at both ends. The lever 20 is moved to its extreme upper position and the lever 33 to its extreme right hand position as indicated in Figure 9.

25 In this position abutment 38' presses the plate 26 downwards through the pin 39 thus pressing pivots 30 and 45 downwards and opening both clips. The cable can now be threaded into or out of the apparatus by the action of the hand alone.

30 In the apparatus as illustrated in the drawings there are only shown two different positions for the pivotal axis of the lever 20 but it will be understood that the number of ratios can be increased and they can have any values without the invention being in any way modified or affected.

35 The details of construction of the apparatus can also be varied wth the scope of the appended claims.

40 What I claim is:—

1. Apparatus for hauling on a rope comprising a first rope clip, a second rope clip, means for moving said second clip towards and away from said first clip, controlling means for holding one clip in action when the other is out of action, and means for reversing the action of said controlling means with respect to the direction of movement of said clip moving means.

45 2. An apparatus for hauling on a rope comprising an automatic one way rope clip, a second automatic one way rope clip acting in the same direction as said first'clip, means for moving said second clip towards and away from said first clip, and means set in action at will for reversing the normal operation of said clips.

50 3. A rope clip comprising a pair of cheeks, a plurality of parallel links pivoted to said cheeks, a slotted first jaw pivoted to said links, a link not parallel to said first links pivoted to said cheeks, a second jaw, a pivot pin connecting said second jaw to said second link and passing through a slot in said first jaw, and a spring urging said jaws into the gripping position.

55 4. A rope hauling apparatus comprising a body, a first rope clip secured in said body, a second rope clip slidable in said body towards and away from said first clip, means for reciprocating said second clip, a reversing member slidably connected to said body adapted to open and close said first clip, means for holding said reversing member in frictional engagement with said body, a slidable member slidably connected to said second clip adapted

to open and close said clip when slid in relation thereto, abutments on said reversing member in the path of said slidable member and means for putting said reversing member and slidable member out of action at will.

5 5. A rope hauling appliance comprising a body, a first one way rope clip secured in said body, a second one way rope clip acting in the same direction as said first clip movable in said body towards and away from said first clip, means for so moving said second clip, sliding means on said second clip adapted to open and close said second clip, other sliding means on said body adapted to open and close said first clip, and abutments on said other sliding means in the path of said sliding means on said second clip.

6 6. A rope hauling appliance comprising a body, a first one way rope clip secured in said body, a second one way rope clip acting in the same direction as said first clip movable in said body towards and away from said first clip, means for so moving said second clip, sliding means on said second clip adapted to open and close said second clip, other sliding means on said body adapted to open and close said first clip, abutments on said other sliding means in the path of said sliding means on said second clip and means for putting both said sliding means out of action.

7 7. A rope hauling apparatus comprising a body, a first automatic one-way rope clip secured in said body, a second automatic one-way rope clip slidable in said body towards and away from said first clip, means for reciprocating said second clip, a friction device associated with each clip only sufficiently strong to hold the clip open when it is not gripping the loaded rope, means associated with said first clip for closing said second clip when the latter reaches its furthest position from said first clip and for opening said first clip when said second clip has been so closed, and means associated with said second clip for closing said first clip when said second clip reaches its nearest position to said first clip and for opening said second clip when said first clip has been so closed.

8 8. A rope hauling appliance comprising a body, a first one way rope clip secured in said body, a second one way rope clip acting in the same direction as said first clip movable in said body towards and away from said clip, means for so moving said second clip, a slidable plate frictionally held to said body and movable laterally into and out of a position in which it is enabled to open and close said first clip by longitudinal movement, a second slidable plate frictionally held to said second clip and located in an aperture in said first slidable plate, said aperture being so shaped as to move said second plate laterally with said first plate but to permit relative longitudinal movement, said second plate being so moved laterally into a position in which it is enabled to open and close said second clip by longitudinal movement when said first plate is in the corresponding position with respect to said first clip, and abutments on said first plate engaged by said second plate sufficiently before the ends of its stroke to cause said first clip to close before said second clip opens at the end movement of said second clip in the opposite direction to that in which said clips open and to cause said second clip to close before said first clip opens at the end of the movement of said second clip in the direction in which said clips open.
